UNITED STATES PATENT OFFICE

151,604

DESIGN FOR A COUPLER FOR TOWING VEHICLES

Alfred Denney, Los Angeles, Calif.

Application July 22, 1947, Serial No. 140,449

Term of patent 14 years

(Cl. D14—23)

To all whom it may concern:

Be it known that I, Alfred Denney, a citizen of the United States of America and a resident of the city and county of Los Angeles, in the State of California, have invented a new, original, and ornamental Design for a Coupler for Towing Vehicles, of which the following is a specification, reference being had to the accompanying drawing, forming a part thereof.

In the drawings:

Figure 1 is a side perspective view of a coupler for towing vehicles, showing my new design, and

Figure 2 is a vertical section taken substantially along the line 2—2 of Figure 1.

I claim:

The ornamental design for a coupler for towing vehicles, substantially as shown.

ALFRED DENNEY.
